UNITED STATES PATENT OFFICE.

LEE DECK, OF WINFIELD, KANSAS.

GAS BURNER.

Application filed November 6, 1926. Serial No. 146,656.

The invention relates to fluid burners and more especially to the class of gas burners.

The primary object of the invention is the provision of a burner of this character, 5 wherein the construction thereof enables the consumption of gas whether under light or heavy pressure and is designed to permit the grouping of a plurality of burners, so that such group can be used in furnaces for 10 manufacturing purposes or under a particular arrangement for domestic purposes.

Another object of the invention is the provision of a burner of this type, wherein the gaseous fluid is properly mixed with air 15 in a mixing chamber so as to assure perfect combustion with maximum heating qualities, the burner proper being of novel form, so that it can be grouped with other similar burner elements to increase the capacity of 20 the equipment, when associated with a furnace or other like structure used for manufacturing or domestic purposes.

A further object of the invention is the provision of a burner of this character, 25 wherein the construction thereof enables the nesting of the same so that a plurality of like burners can be used in banked or grouped assemblage, the burner proper being readily disassembled, to permit easy 30 cleaning thereof, repairing or replacement of any of its parts.

A still further object of the invention is the provision of a burner of this character, which is extremely simple in its construction, 35 thoroughly reliable and efficient in its purpose, strong, durable, and inexpensive to manufacture and install.

With these and other objects in view, the invention consists in the features of construction, combination and arrangement of parts, as will be hereinafter more fully described, illustrated in the accompanying drawings, showing the preferred embodiments of the invention, and pointed out in 45 the claims hereunto appended.

In the accompanying drawings:

Figure 1 is a top plan view showing a bank or group of gas burners or a multiple combination of individual unit burners for 50 an industrial gas burner outfit, constructed in accordance with the invention.

Figure 2 is an enlarged fragmentary vertical longitudinal sectional view through adjacent gas burner units, showing the sup-

ply pipe for the fuel in association therewith.

Figure 3 is an end elevation of one of the gas burner units with the brackets for the supply pipe connected therewith.

Figure 4 is a top plan view of the individual gas burner unit, with the cover element removed therefrom.

Figure 5 is a bottom plan view of the cover element removed from the burner.

Figure 6 is a plan view of the bottom 65 section of one of the gas burner units.

Figure 7 is a side elevation thereof.

Similar reference characters indicate corresponding parts throughout the several views in the drawings.

Referring to the drawings in detail, 10 designates generally a portion of the gas main pipe having leading therefrom the intermediate and outer branch supply pipes 11 and 12, respectively, which are disposed in spaced parallel relation to each other and of the required length, lying in the same plane one with the other, the outer ends of each of the branch pipes being fitted with a removable cap 13 tapped thereon. These 15 branch pipes 11 and 12, each serve a plurality of individual gas burner elements hereinafter fully described.

Upon each branch pipe 11 and 12, is a bracket 14 supporting superposed relative 20 to said pipes the individual gas burner or element, which comprises a substantially squared or rectangular shaped box like body 15, the latter being fastened to the bracket through the medium of a screw 16, although any other suitable fastener may be employed, the bracket being cut away to provide a seat 25 25 to accommodate the body 15 as is clearly shown in Figure 2 of the drawings. This body 15 is open at opposite ends and at a point removed from the open upper end is formed a web or partition 18 having a central circular opening 19 providing an outlet 30 while above said partition at the corners of the body 15 are formed bearing lugs 20 upon 35 which rest a removable cover element or member 21. The cover element or member 21 is of substantially squared or rectangular shape having cup formation with the downwardly tapered marginal wall 22 provided 40 externally at the corners thereof with ribs or flanges 23 which engage in the corners of the body 15 at the upper open end there-

of, so that between the said body and the wall 22 of the cover element or member 21 are interrupted spaces 24 for the passage of products of combustion from within the 5 burner element as will be apparent.

Removably fitted in the lower open end of the body 15 of the burner element is a bottom section 25 having a central aperture or opening 26 forming an intake, the latter 10 being disposed in vertical axial alignment with a perforation 27 formed in the branch pipe 11 or 12. This bottom section 25 at one side is formed with an ear 28 into which is tapped a screw 29 or other fastener inserted 15 through a suitable hole in the side wall of the body 15, so that in this manner the said bottom section 25 will be made fast to the body member. The bottom section 25 is formed with a lateral marginal flange 30 20 throughout, which is adapted to abut the marginal edge of the lower open end of the body 15 of the burner element as is clearly shown in Figure 2 of the drawings.

It is understood that the number of brackets 25 upon each branch pipe 11 or 12 corresponds to the number of individual gas burner elements employed to make up the set, bank, or group, for use in a furnace for manufacturing or domestic purposes. These 30 brackets 14 each is made fast upon the branch pipe through the medium of a set screw 31 or other fastener, so that the said brackets can be adjusted for regulating the desired assemblage of the gas burner units 35 in the grouping or banking thereof.

Arranged exteriorly on each body 15 at one side thereof is a single spacer lug 32, while on another side at right angles to this first mentioned side is another single spacer lug 33 and on still another side directly opposite the last named side is a pair of spaced lugs 34, which latter cooperate and interlock 40 with the lug 33 on the side of an adjacent individual gas burner unit, so that in this manner these units upon one branch pipe 45 will be interlocked with each other in spaced relation to one another in row formation. The lugs 32 serve to space the individual gas burner units of the respective rows from each 50 other as is clearly shown in Figure 1 of the drawings.

The individual gas burner units of each row are united together through the medium of a tie bolt 35 having the usual nut 36 55 threaded thereon and trained through a spacer sleeve 37 located between adjacent units, the bolt 35 being passed through suitable apertures formed in side walls adjacent each other of the bodies 15 of said units.

60 The web or partition 18 in each body 15 separates the burner head from the mixing chamber 38, the burner head being constituted by the upper open end and the cover element or member 21. The gas fluid from 65 the main 10 is supplied to the burner units

through the port 27 and opening 26 into the chamber 38, whence air will mix therewith and this mixture will rise to contact with the base of the cover element or member 21, thence the said mixture will be caused to 70 spread and pass out marginally of said cover element or member 21 through the spaces 24, where the mixture is ignited. Asbestos packing, fire clay, or other similar materials may be carried within the cover element or member 21 in the depression formed therein as 75 will be clearly apparent.

What is claimed is:—

1. In a burner element a hollow body portion open at its top and bottom, a removable bottom plate extending into said body portion, abutting against the lower edge of the latter and formed with an axial opening providing an inlet, a horizontally disposed web, corresponding in contour to the inner contour of said body portion, integral with the inner face of the latter and forming in connection with said bottom plate a mixing chamber, said web positioned below the open top of the body portion and provided with an axial opening forming an outlet aligning with the opening in said plate, lugs integral with the web and inner face of the body portion below the open top of the latter, and a cover element seated on said lugs and having spaced lateral flanges for positioning the cover element from the inner face of the body portion. 90

2. In a burner element a hollow body portion open at its top and bottom, a removable bottom plate extending into said body portion, abutting against the lower edge of the latter and formed with an axial opening providing an inlet, a horizontally disposed web, corresponding in contour to the inner contour of said body portion, integral with the inner face of the latter and forming in connection with said bottom plate a mixing chamber, said web positioned below the open top of the body portion and provided with an axial opening forming an outlet aligning with the opening in said plate, lugs integral with the web and inner face of the body portion below the open top of the latter, a cover element seated on said lugs and having spaced lateral flanges for positioning the cover element from the inner face of the body portion, and an inwardly extending ear carried by said bottom plate and detachably connected with said body portion. 100 110 115

3. In a burner element a hollow body portion open at its top and bottom, a removable bottom plate extending into said body portion, abutting against the lower edge of the latter and formed with an axial opening providing an inlet, a horizontally disposed web, corresponding in contour to the inner contour of said body portion, integral with the inner face of the latter and forming in connection with said bottom plate a mixing 125 130 135

chamber, said web positioned below the open top of the body portion and provided with an axial opening forming an outlet aligning with the opening in said plate, lugs

- 5 integral with the web and inner face of the body portion below the open top of the latter, a cover element seated on said lugs and having spaced lateral flanges for positioning the cover element from the inner face of the 10 body portion, a combined spacing and locking lug integral with the outer face of said body portion at one side thereof, and a pair of spaced combined spacing and locking lugs integral with the outer face of the body 15 portion on the other side thereof, the said lugs on the outer face of the body portion coacting with the lugs on adjacent burner elements for coupling them together.

4. In a burner element a hollow body portion open at its top and bottom, a removable bottom plate extending into said body portion, abutting against the lower edge of the latter and formed with an axial opening providing an inlet, a horizontally disposed web, 20 corresponding in contour to the inner contour of said body portion, integral with the inner face of the latter and forming in connection with said bottom plate a mixing chamber, said web positioned below the open 25 top of the body portion and provided with an axial opening forming an outlet aligning with the opening in said plate, lugs integral with the web and inner face of the body portion below the open top of the latter, a cover element seated on said lugs and having spaced lateral flanges for positioning the cover element from the inner face of the body portion, a combined spacing and locking lug integral with the outer face of the body 30 portion at one side thereof, a pair of spaced combined spacing and locking lugs integral with the outer face of the body portion on the other side thereof, said lugs on the outer face of the body portion coacting

with the lugs on the adjacent burner elements for coupling them together and an inwardly extending ear carried by said plate and detachably connected to said body portion.

5. In a burner element a hollow rectangular body portion open at its top and bottom and having one of its sides provided with a laterally extending spacing lug, another of its sides disposed at right angles to the first mentioned side provided with a laterally extending spacing lug and another of its sides disposed at right angles with the first mentioned side provided with a pair of opposed, spaced laterally extending combined locking and spacing lugs, said 50 lugs arranged above the bottom of said body portion, a web of the same contour as the inner contour of said body portion and formed integral throughout with the inner face of the latter below its open top, said 55 web provided with an opening, and lugs integral with the upper face of the web for supporting a cover member.

6. In a burner element a hollow body portion open at its top and bottom, with a web 70 of the same contour as the inner contour of the body portion and formed integral with the inner face of the latter, a bottom plate positioned against the lower end of and extending into the body portion and forming in 75 connection with the web a mixing chamber, means for detachably securing said bottom plate to said body portion, a cover element removably mounted in the open top of the body portion, means for spacing the cover 80 element from the inner face of the body portion and from said web, and said plate and web provided respectively with an intake and an outlet for said chamber.

In testimony whereof, I affix my signature 85 hereto.

LEE DECK.
